UNITED STATES PATENT OFFICE.

AURA E. WHITEHEAD, OF DETROIT, MICHIGAN, ASSIGNOR TO FARRAND & VOTEY ORGAN COMPANY, OF DETROIT, MICHIGAN, A CORPORATION OF MICHIGAN.

PIANO-PLAYER.

SPECIFICATION forming part of Letters Patent No. 705,000, dated July 15, 1902.

Application filed May 18, 1901. Serial No. 60,922. (No model.)

To all whom it may concern:

Be it known that I, AURA E. WHITEHEAD, a citizen of the United States, residing at Detroit, in the county of Wayne and State of Michigan, have invented certain new and useful Improvements in Piano-Players, of which the following is a specification, reference being had therein to the accompanying drawings.

- 10 The invention consists in the construction of a piano-player, and particularly in the construction and arrangement of the parts in the upper part of the case, whereby the construction is cheapened and simplified and where-
15 by, further, the tracker-board and motor are so disposed that a folding-in or movable ful-
crum-bar may be employed which may be moved into a stored position or projected out-
side the case; further, in the construction
20 of the case whereby the aperture through
which the fulcrum-bar and playing-fingers are projected may be practically closed in the op-
erating position and entirely closed in the
stored position of the fulcrum-bar; further,
25 in the construction of the fulcrum-bar itself
and the manner of attaching the fulcrum-
blocks thereto, and, further, in the construc-
tion of the playing-fingers and in the con-
struction, arrangement, and combination of
30 the various parts, as more fully hereinafter
described.

In the drawings, Figure 1 is a section through the casing, showing the fulcrum-bar and play-
35 ing-fingers in elevation in their vertical posi-
tion within the case, the tracker-range and
trunk for the motor being shown in vertical
central section. Fig. 2 is a similar section
through the right-hand part of Fig. 1, show-
ing the playing-fingers extended as in oper-
40 ating position. Fig. 3 is a longitudinal sec-
tion on line αx of Fig. 1. Fig. 4 is a per-
spective view of the upper part of the casing
closed. Fig. 5 is a perspective view of a part
of the fulcrum-bar. Fig. 6 is a section there-
45 through, showing one of the playing-fingers
partly in section. Fig. 7 is a horizontal sec-
tion through Fig. 5. Fig. 8 is a vertical lon-
gitudinal section through the regulating-valve
at the right hand of Fig. 3.

- 50 A represents the case of a piano-player.

B is the top section of the case, which is above the action C. The action I have simply indicated as a rectangular box, in which the valves and pneumatics are located, being combined and arranged in any desired manner. 55 The top of the action forms a substantially horizontal partition across the case, extending nearly from side to side thereof, all as plainly shown in Fig. 1. The action is secured to the case in any desired manner. 60

At each end of the case and at the rear side are secured brackets D, in which are pivoted the brackets D', to which is secured the fulcrum-bar E. These brackets are so combined with the case that the fulcrum-bar may be 65 turned so as to project the playing-fingers F, which are pivoted on the fulcrum-bar, outside the case, as shown in Fig. 2, or may be turned with the fingers inside the casing, as shown in Fig. 1. To permit of this turning 70 in or out of the case, I provide in the rear of the case the two doors G and G', having their dividing-line directly above the fulcrum-bar. The lower door G' is of such height as to permit of the projection through the casing of 75 the fulcrum-bar and the playing-fingers in operating position, while the door G is necessarily opened in projecting these parts outside the case, but as soon as they are outside may be turned down, with its lower edge 80 directly above the fulcrum-bar, so as to close from view the inside of the case, with its un-
finished operating parts. In this way the only operating parts that are exposed are the fingers and possibly part of the fulcrum-bar 85 with the particular construction of the case herein shown. When the case is closed up, as shown in Fig. 4, it has a finished exterior appearance, as shown.

H is a front hinged door which forms the 90 front of the tracker-board box I, in which are the tracker-board I' and the rolls for the music-sheet. This tracker-board box is located substantially midway the length of the case and at one side of the middle line, as plainly 95 shown in Fig. 1. This gives ample room beside the tracker-board box above the action in which the fulcrum-bar and the playing-fingers may be turned or moved inside of the casing. 100

The pneumatic-motor J is arranged at one end of the tracker-board box and likewise at one side of the center longitudinal line of the action. This pneumatic-motor is for driving 5 the music-sheet and is of the usual construction, comprising a series of pneumatics connected to a crank-shaft for imparting motion thereto.

At one end of the machine, within the casting and leading up from the end of the action, is a wind-trunk K, which connects into a horizontal wind-trunk K', which extends longitudinally of the action just in rear of the tracker-board box, as plainly shown in 15 Figs. 1 and 3. The wind-trunk K connects into the regulating-bellows L through the port a, and the port b connects from this bellows into the wind-trunk K'.

c is a light spring secured at one side of 20 the port a and extending with its free end over the same, the free end being contacted by an adjustable contact d, secured to the movable port e of the bellows L, all so arranged that as the air is exhausted from the 25 bellows L more or less it will proportionately close the port a, and consequently maintain a substantially uniform pressure in the trunk K' regardless of variation in pressure in the trunk K due to the movement of the pedals 30 by the operator.

M is a tension-spring for the bellows L.

Secured to the under side of the bellows L is a valve-casing N. Leading from the trunk K to the box N is a port h, and from the box 35 N to the trunk K' is a port i.

O is a valve adapted to close the passage-way through the valve-box N. When the valve O is open, a by-pass is formed from the trunk K to the trunk K' or through the port 40 h, box N, and the port i, so that the air does not have to pass through the regulating-bellows L. This is used ordinarily in rewinding 45 music-sheets. By thus arranging the regulating-valve at one end of the tracker-board box and the pneumatic-motor at the other end thereof, with the trunk K' connecting the two, as shown, I obtain an exceptionally 50 compact arrangement of the parts, and the motor and regulating-bellows being above the action can be readily reached for repairs or adjustment by simply removing the top of the case or even opening the doors G G'. It 55 also permits of arranging in the top of the case the stored fulcrum-bar and playing-fingers.

The construction of the fulcrum-bar and playing-fingers is illustrated in Figs. 5, 6, and 7. The bar E is preferably a wooden bar and is provided on its outer surface with 60 a series of vertical gains k. These gains have at the desired points between them the ribs l. Secured in the gains k and on the faces of the ribs l are a series of fulcrum-blocks m, which are shown in Fig. 5. These blocks have at 65 their end the bifurcated portion n, in which is journaled a playing-finger F. These blocks are also preferably provided with a shoulder

o, engaging on the under side of the fulcrum-bar, and they are secured to the fulcrum-bar in any suitable manner, preferably by means 70 of screws p, passing through the body of the block and into the bar. This arrangement gives me the desired difference in the location of the fulcrums for the playing-fingers for the black and white keys, respectively, 75 and is a construction which is not only simple and economical, but is strong and durable, with no chance of the turning or loosening of the fulcrum-blocks after they are once secured in position. The inner ends of the 80 playing-fingers F are preferably bored with a longitudinally-extending hole, and in this is inserted an elongated counterweight F', which always maintains the inner ends of the playing-fingers in contact by gravity with the 85 upper end of the actuating-bars O, which are connected to the pneumatics and operated thereby.

I do not herein claim in such a device as I have shown the finger-levers projecting without the case in their playing position and a common actuating means for retracting the levers within the case nor such a combination, including the common fulcrum-bar, broadly, for such combination is shown, described, 95 and claimed in my previous application No. 27,488.

What I claim as my invention is—

1. In a piano-player, a vertical case, an action-case arranged in the case below the top, a tracker-board box secured to the top of the action near the middle, a wind-trunk extending up from the action at one side, a horizontal wind-trunk extending across the top of the action behind the tracker-board box and 105 the pneumatic-motor on the action beside the tracker-board box, to which the horizontal trunk connects.

2. In a piano-player, a case, an action arranged in the case below the top, a tracker-board box secured to the top of the action at one side near the middle line of the case, the motor on top of the action at the end of the tracker-board box, leaving the other side of the top of the action clear, and a movable 115 fulcrum-bar having the playing-fingers pivoted thereon, adapted to be moved within the case above the action beside the tracker-board box and motor.

3. In a piano-player, a case, an action arranged in the case below the top, the tracker-board secured to the top of the action, a wind-trunk extending up at one end of the action, and a horizontal wind-trunk extending across the top thereof, a pressure-regulator on the 125 top of the action at one end, connected to said wind-trunk as described, and a pneumatic-motor at the other end of the action, to which said trunk connects.

4. In a piano-player, a case, an action arranged in the case below the top, the tracker-board secured to the top of the action, a wind-trunk extending up at one end of the action and a horizontal wind-trunk extending longi-

tudinally across the same, a regulating-bellows secured to the said trunk at one end, a valve-casing secured to the bellows and connected to the trunk on both sides of the regulating-bellows connection, a valve in said casing and a pneumatic-motor at the other end of the action into which said wind-trunk connects.

5. In a piano-player, the combination of a case, an action in the case, a fulcrum-bar, the playing-fingers pivoted thereon, said bar being supported movably to withdraw the fingers in the case or to project them therefrom, of two doors for closing the aperture in the case through which the fingers are projected, one door extending down nearly to the upper face of the projecting portions, for the purpose described.

6. In a piano-player, a fulcrum-bar, having a series of vertical gains in its face, and a series of interposed strips or ribs formed between the gains, of fulcrum-blocks secured to said bar in the gains, other fulcrum-blocks secured on the outer faces of said ribs and projecting beyond the bar, and playing-fingers pivoted in such projections.

7. In a piano-player, a fulcrum-bar having a series of vertical gains in its outer face, and a series of interposed strips or ribs between the gains, of fulcrum-blocks *m* secured to said bar in the gains, other fulcrum-blocks secured on the outer faces of the ribs, the bifurcated portion *n* projecting below the bar and the shoulder *o* on the blocks bearing against the under face of the fulcrum-bar.

8. In a piano-player, the wind-trunk *k*, the regulating-bellows on one side thereof and the valve-case *N* on the other side, the wind-trunk *K'*, the ports *a b* connecting the wind-trunks with the bellows, the valve *c* for the port *a*,

the ports *h* and *i* connecting the wind-trunks with the valve-case, and the valve *O* for controlling the by-pass through the valve-case.

9. In a piano-player, a case, an action arranged in the case below the top, a pivoted fulcrum-bar having the playing-fingers pivoted thereon, movable to a position within the case above the action with the playing-fingers in a vertical position at the rear side of the casing, or into a horizontal position projecting without the case.

10. In a piano-player, a case, an action arranged in the case below the top, a movable fulcrum-bar having the playing-fingers pivoted thereon movable within the case to a vertical position above the rear side of the action, and the tracker-board, above the action at the forward side thereof.

11. In a mechanical playing attachment for keyboard musical instruments, the combination of a casing, a pneumatic-action therein, a series of vertically-movable push-rods operated by said action, a series of finger-levers arranged in their playing position, in a substantially horizontal plane with their key-actuating ends projecting without the casing and their inner ends in proximity respectively to said push-rods, a fulcrum-bar to which said levers are pivoted, and rocking brackets to which said bar is attached arranged laterally in the operating position of parts and adapted to be swung upward to carry said levers into a substantially vertical plane within the casing.

In testimony whereof I affix my signature in presence of two witnesses.

AURA E. WHITEHEAD.
